US0D1103766S

(12) **United States Design Patent** (10) **Patent No.:** **US D1,103,766 S**
(45) **Date of Patent:** **** Dec. 2, 2025**

(54) **BOTTLE LID**

(71) Applicant: **Joe Brands, LLC**, Nashville, TN (US)

(72) Inventor: **John Rosen**, Nashville, TN (US)

(73) Assignee: **Joe Brands, LLC**, Nashville, TN (US)

(**) Term: **15 Years**

(21) Appl. No.: **29/947,245**

(22) Filed: **Jun. 13, 2024**

(51) LOC (15) Cl. **07-02**

(52) U.S. Cl.

USPC **D7/392.1**; D9/454

(57) **CLAIM**

The ornamental design of a bottle lid as shown and described.

DESCRIPTION

FIG. 1 is an isometric view of a bottle lid illustrating the new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof;

FIG. 7 is a bottom view thereof;

FIG. 8 is an isometric view of a bottle lid illustrating the new design, shown in an environment of use;

FIG. 9 is a front elevational view thereof;

FIG. 10 is a rear elevational view thereof;

FIG. 11 is a right-side elevational view thereof;

FIG. 12 is a left-side elevational view thereof;

FIG. 13 is a top view thereof; and,

FIG. 14 is a bottom view thereof.

The broken lines shown in the drawings depict portions of the article that form no part of the claimed design.

1 Claim, 14 Drawing Sheets
